ASSEMBLING MACHINE

George R. Eckstein, Milford, Conn., assignor to Remington Arms Company, Inc., Bridgeport, Conn., a corporation of Delaware

Application November 1, 1946, Serial No. 707,092

12 Claims. (CL. 86—1)

1

This invention relates to machines for assembling a plurality of small components and, in the embodiment illustrated in the drawings, contemplates the assembly of three components of an electric primer comprising a tubular body, a contact button and a perforated sheet of insulating material, which sheet is interposed between the body and the contact button.

In the drawings:

Fig. 1 is a plan view of the machine from which, for greater clearness, outlines of many concealed or partially concealed parts have been omitted.

Fig. 2 is a longitudinal sectional elevation substantially on the line 2—2 of Fig. 1.

Fig. 3 is a somewhat diagrammatic fragmentary sectional elevation on a portion of the line 2—2 of Fig. 1 intended particularly to show the progress of components and assemblies through the machine.

Fig. 4 is a view similar to Fig. 3, showing punches, movable dies and component transfer stems in retracted position.

Fig. 5 is a detail of a contact button holding and guiding device substantially on the line 5—5 of Fig. 3.

Fig. 6 is a fragmentary transverse sectional elevation substantially on the line 6—6 of Fig. 1.

Fig. 7 is an enlarged fragmentary horizontal section substantially on the line 7—7 of Fig. 6.

Fig. 8 is a diagrammatic end view of the drive shaft and cams thereon.

Fig. 9 is a perspective of the reciprocating tape feed assembly.

Fig. 10 is a detached longitudinal elevation of the means for removing assemblies ejected from the dies.

Fig. 11 is a partial vertical sectional view on the line 11—11 of Fig. 1.

General description

The invention, in a specific aspect, contemplates a simple rugged and highly accurate machine for the assembly of the three components of an electric primer into a finished unit. In general construction and functioning the machine comprises a stationary die plate having an upwardly opening passage through which primer bodies are introduced. The lowermost body of a stack is transferred into an assembly die in which there are assembled into the body an insulating disk and a contact button. The assembly is then transferred to a second die, mounted in the same fixed die plate, in which the assembly is crimped into a finished unloaded primer. The transfer, assembly and crimping tools are all mounted on two reciprocating gates located on opposite sides of the transfer plate and carried on guide rods extending through the transfer plate. The tools are so mounted and

2

moved that their work-engaging ends are at all times held in and guided by fixed parts associated with the die holders. Contact buttons are introduced into the upper portion of one of the two reciprocating gates and by the movement of the gate, augmented by a separate reciprocating plunger, are assembled into the primer body held in the assembly die. A tape of insulating material is introduced into one side of the machine and, having been appropriately perforated, passes between the assembly die and the button advancing means. A cutting punch associated with the left gate severs a disk from the tape, and this disk is transferred into the primer body by the advancing contact button. The disk is of such diameter that a marginal portion thereof folds around the contact button in a way which insures insulation of the button from the body. The primer thus assembled is thereupon pushed out of the assembly die and drops through a short passage into position for insertion, by an assembly stem on the right gate, into a crimping die in which an end portion of the body is crimped over the contact button and the insulating material by a crimper head mounted upon the right gate.

In the following description, the terms "right" and "left" refers to the position of the parts as illustrated in the drawings in which the machine is viewed from the side opposite the tape supporting table and adjacent to cam 20 which operates the right gate.

Frame and driving means

Referring now to the drawings, the machine comprises a base 10 of heavy construction, having secured thereto end plates 11 and 12 and a center plate 13, all of which are suitably apertured and recessed to receive the various working parts to be described. Secured to and extending between the end plates 11 and 12 and through the center plate 13 are four guide rods 14. A drive and cam shaft 15, held in bearings in suitable supports 16 secured to the base 10 and driven from an external source of power by suitable means, such as a sprocket 17, carries a series of cams which control the operation of all moving parts. The center plate 13, as well as end plates 11 and 12, is rigidly secured to the guide rods 14. Slidably mounted on guide rods 14 are a right gate assembly 18 and a left gate assembly 19. The right gate assembly is actuated by a cam 20 secured to cam shaft 15 through a cam follower 21 carried by a lever 22 pivoted on an arbor 23 carried in suitable bearings in end plate 11. Arbor 23 has secured thereto a lever 24 which is joined to lever 22 by a shear pin 25, this shear pin connection being typical of several which are used throughout the machine. In general, moving parts are positively actuated on

their working stroke and are spring returned, security against damage in the event of jams being effected by the use of shear pin connections. The spring which holds cam follower 21 in contact with the periphery of cam 20 is shown at 26. As the springs 50 and 26 return the cam followers after passing the high spot of the cams, there is a tendency for the shaft 15 to speed up. Over-running is prevented by the employment of a brake 140 held in engagement with a pulley 141 on shaft 15 by a spring 142. Arbor 23 carries a crank 27 and a crank pin 28, to the end portions of which are secured short connecting rods 29, the opposite ends of such rods being secured to an arbor 30 having journal bearings in elements 15 of the right gate assembly 18, which elements will be presently described.

Right gate

The function of the right gate assembly 18 is to support and reciprocate a body transfer stem and an assembly transfer stem; such assembly comprises a pair of vertically disposed side blocks 31, each apertured to receive and reciprocate upon two of the guide rods 14. Within the apertures are placed suitable anti-friction bearings, and blocks and bearings are of such length as to insure an accurate rectilinear movement upon the guide rods. The blocks 31 are rigidly secured together by means of a transversely extending top plate 32 and a similar bottom plate 33. Likewise secured to the plates 32 and 33 is a substantially centrally disposed transfer stem holder mounting block 34 in which is secured, by suitable means such as a screw 35, a stem holder 36. The top and bottom plates 32 and 33 comprise ribs 32a and 33a engaging respectively with the sides of the side blocks 31 and the punch holder mounting block 34, which insure the correct transverse relative positioning of these parts and add to the rigidity of the assembly. Arbor 30 passes through aligned apertures in the side blocks, and the stem holder mounting block and connecting rods 29 are located between the side blocks and the stem holder mounting block. The stem holder 36 receives and supports a body transfer stem 37 and an assembly transfer stem 38, said stems bottoming in the holder 36 against wedge shaped adjustable keys 39 by which the effective length of the stems can be accurately adjusted. Fig. 2 shows the right gate assembly in retracted position, and it will be noted that both stems 37 and 38 are well within apertures in the center plate 13; this construction prevents any injury to the stems and insures their accurate alignment with the work as hereinafter described.

Left gate assembly

The left gate assembly is similar in general construction to the right gate assembly, comprising a pair of side blocks 40, each apertured to receive a pair of the guide rods 14 and joined together by a top plate 41 and a bottom plate 42, to which plates there is also secured a centrally disposed punch and die holder mounting block 43. The assembly is reciprocated on guide rods 14 by a cam 44 secured to the drive shaft 15 and actuating a cam follower 45 mounted on a lever 46 pivoted on an arbor 47 journalled in the left end plate 12 and having secured thereto an arm 48 joined by a shear pin 49 to one extremity of lever 46. Cam follower 45 is held in contact with the periphery of cam 44 by a suitable spring, such as 50. Upon arbor 47 is mounted a crank 51 carrying crank pin 52 which supports a pair

of connecting rods 53, the opposite ends of which are secured to an arbor 54 having journal bearings in the side blocks 40 and the punch and die holder mounting block 43.

Mounted in or associated with the left gate assembly are tools for making a desired pattern of perforations in a continuous tape of insulating material, cutting from the tape a disk including the perforations, feeding a contact button into engagement with the disk and assembling both the insulating disk and the contact button into a primer body, and crimping the body over button and insulation. The assembly tools are located opposite and cooperate with the body transfer stem 37, and the crimper head is located opposite and cooperates with the assembly transfer stem 38. The perforating of the tape is a preliminary operation, and there are no counterpart tools associated with the right gate assembly 18.

The tape perforating tool is carried in a bracket 55 secured to the side block 40 adjacent the tape feed device to be described. Said bracket comprises lateral projections 56 and 57, between which is received a head 58 of the tape perforating assembly. Projection 57 is slotted from its free end to receive punches 59 which project from the head 58 toward and through apertures 591 in a block 592 (Figs. 6 and 7) held in slots in 30 a die plate 86 and cover plate 87 secured to center plate 13 and to be further described. Block 592 is transversely apertured to receive the insulating tape, and behind the tape and in alignment with the punch holding apertures 591 are 35 a second set of apertures into and through which the punches advance, delivering the tape punchings into a counterbore 593 in block 592, which counterbore communicates with a punching delivery tube 594. Any desired pattern of 40 punches can be used. An assembly of three punches has been illustrated, said punches being so spaced as to provide openings through the insulation which are spaced only a short distance from the margin of the button supporting flange 45 of the primer body. In this way, the path of current travel is short, as compared with the conventional single centrally disposed perforation; likewise, the central portion of the insulating disk remains intact, and the stretching and failure which characterize centrally perforated disks is obviated.

To the face of the punch and die holder block 43 is secured a plate 60, the upper portion of which is slotted to provide a vertical passage 61 for contact buttons which are supplied through a feed chute 62 secured to block 43. Plate 60 is likewise recessed to receive the tape blanking punch 63, the end portion of which remains at all times within a guide bushing 631 held in the 60 fixed die assembly to be described. Said punch comprises a hollow stem, the end portion of which cooperates with a blanking die, to be described, to sever a disk of insulation from the tape. Contact buttons supplied through slot 61 in turn assume a position in the bottom of this slot between a contact button transfer stem 64 and a button retainer identified generally by numeral 65 and illustrated in Fig. 5. Reference is also made to Figs. 3 and 4, each of which shows a column of 65 contact buttons C in the position they occupy in the slot 61. In Fig. 4, the lowermost contact button rests on the bottom of slot 61 and supports the column of buttons above it. In Fig. 3 the transfer stem 64 is in advanced position, and the lowermost button rests upon the periphery of

this stem. The buttons being disks which are of small thickness with respect to their diameter, it is necessary to retain the lowermost button in a vertical position until it is engaged and moved by the punch. This purpose is served by the retainer 65. Said retainer is a disk of diameter substantially greater than the diameter of the buttons and occupies a recess in plate 60 adjacent the head of blanking punch 63. The disk may be considered as comprising three identical sectors, one of which will be described: An outer arcuate slot 66 of substantial length is joined to a radial slot 67 by an enlarged aperture 68. An inner and shorter arcuate slot 69 is joined to a short radial slot 70 by an enlarged aperture 71. There is thus formed a tongue 2 supported by a flexible arm 73, and a tongue 74 which is radially joined to the body of the disk and is thus less easily displaceable than tongue 72. The arcuate inner margins of the three tongues 72 define a circle which is of slightly less diameter than the diameter of a contact button C, while the arcuate inner margins of the three tongues 74 define a circle of a diameter substantially equal to the diameter of a contact button. The tongues 72 are thus able to retain the lowermost button in a vertical position until it is engaged by the transfer stem or punch 64. Upon such engagement the tongues 72 are displaced to permit passage of the button into and through the hollow stem of the tape blanking punch 63.

It will be noted that the button transfer stem 64, while guided for reciprocation by a bore 64a in the left gate assembly, must be given a separate movement in addition to the movement of said gate assembly, in order to transfer each button in turn through the blanking punch, which is rigidly secured to said gate assembly. The means for so moving stem 64 may be constructed as follows: A cam 75 on drive shaft 15 is engaged by a cam follower 76 mounted on short lever 77 pivoted on the boss 78 of one of a pair of arms 78 secured to an arbor 79 supported in an aperture in the punch and die holding block 43. Lever 77 has a shear pin connection at 80 with an extension of one of the arms 78. The two arms 78 extend upward and leftward, and are pivotally connected at 81 to a pair of arms 82 which are journaled on a cross-head 83 in which the transfer stem 64 is adjustably held. The assembly is retracted and follower 76 held against cam 75 by suitable means such as spring 84, held in a housing 84a and joined to a convenient part of the assembly, such as the end of the button transfer stem 64. The design and timing of cam 75 is such that stem 64 is given its forward movement to transfer a button C from the base of slot 61 through the retainer 65 and hollow blanking punch 63 and into the assembly die (to be described) after the insulating disk has been blanked from the tape by punch 63 in the forward movement of gate assembly 19.

Die assembly

The dies in which the components are assembled and the assembly crimped are rigidly mounted on the fixed center plate 13. The assembly die is accurately aligned with body transfer stem 37, blanking punch 63 and button transfer stem 64; while the crimping die is aligned with assembly transfer stem 38 and a crimpler head 85 carried by the left gate assembly 19 in an appropriately shaped recess in the plate 60. The die holders comprise a die plate 86 and a cover plate 87. The die plate 86 is slotted to pro-

vide a vertical passage 88 communicating with a chute 89 through which the primer bodies B are received in side-by-side relation. When the body transfer punch is retracted, the lowermost body B rests on the bottom of slot 88 (see Fig. 2) which supports it in the position shown in Fig. 4 in alignment with the transfer stem 37 and with an assembly die 90 held in die plate 86. As the transfer punch is advanced it picks up the lowermost body of the stack and advances it into and partly through assembly die 90 to the position shown in Fig. 3. The body being in this position, the blanking punch 63 is advanced to sever a disk of insulating material from the tape T, which disk is carried forward on the end of the blanking punch and presented to the end of the primer body. Thereafter, button transfer stem 64 is advanced, carrying with it a contact button, as heretofore described, engaging such contact button with the disk D of insulation carried on the end of blanking punch 63, and simultaneously moving said disk and the contact button into the primer body. A blanking die 91 cooperates with the blanking punch 63 in severing the disk D from tape T. Tape T is intermittently advanced, by mechanism to be hereinafter described, and it will be noted that the retrograde movement of the tape advancing mechanism occurs while both blanking punch 63 and perforating punches 59 are in advanced position, extending through the tape and thereby holding the tape against backward movement.

Fig. 4 diagrammatically shows the essential elements of the die assembly with the transfer stems and other parts associated with the two reciprocating gates in retracted position. It will be seen that an assembled uncrimped primer lies within the die 90 and that stem 37 is behind another primer body B ready to thrust such body into the die on its next advancing movement. The assembled primer within the die is pushed on through the die by such body B and falls into a second vertical slot 92 which extends entirely through the die plate 86. The inner and lower portion of blanking die 91 is slotted as shown to provide ample clearance for the assembled primer thus ejected from assembly die 90. The lower end of slot 92 is closed by a removable retainer 93 provided with a finger piece 932 and held in place by a key 931 provided with a manipulative handle. Thus, retainer 93 can be removed at will, to facilitate clearing of jams which might occur in feed passage 92. The arcuate upper surface of the retainer is adapted to hold a primer assembly A in alignment with assembly transfer stem 38 and crimpler head 85. Upon each advance of assembly transfer stem 38, the lowermost assembly is withdrawn, the next assembly above resting upon the periphery of stem 38, and moved into and partly through a crimping die 94 (Fig. 3). However, the crimpler head 85 of gate assembly 19 has been previously advanced into contact with the face of die 94, so that the head and die together form substantially a solid and blind die into which the primer assembly is thrust by stem 38. In this movement the end portion of the cylindrical body is turned inwardly to conform to the shape of the cavity in the crimpler head and the assembly of the primer is thus completed. As crimpler head 85 and stem 38 are retracted, the assembled and crimped primer remains in the die 94 from which it is ejected by the forward movement of the next succeeding assembly A upon the assembly transfer stem 38.

To facilitate the downward movement of assemblies ejected from assembly die 90, insure the movement of the lowermost of such assemblies into position to be picked up by stem 38, and to insure the removal of assembled and crimped primers from a position between crimping die 94 and crisper head 85, certain feeding or "knockdown" devices are provided. These comprise a reciprocating feed bar 95 extending downwardly through a vertical slot in the upper portion of die plate 86 and into the upper portion of slot 92, and a substantially vertically reciprocating knock-off plate 96 positioned adjacent the face of crimping die 94. The means for actuating these devices comprises a cam 97 secured to drive shaft 15 and actuating a cam follower 98 carried on a bracket extending from a substantially vertically disposed arm 99 rigidly secured at its upper end to a lever 100 pivoted at 101 to a bracket 102 secured to the left end plate 12. The rearward or leftward end of lever 100 is joined by a link 103 to a lever 104 pivoted on an arbor 105 supported on end plate 12. Said arbor 105 likewise carries a lever 106, and levers 101 and 106 are joined to form a solid frame by a tie-rod 107 and a cross-bar 108. To cross-bar 108 is secured one side of a hinge assembly 109, the opposite side of which is joined to feed bar 95. The knock-off plate 96 is carried by a bracket secured to the bar 99, and roller 98 is held in contact with cam 97 by a spring 991 extending between arm 99 and bracket 102.

Referring to Fig. 8, it will be noted that the cam 97 has two recessed portions, hence there are two reciprocations of the feed bar 95 during each cycle of operation. What might be called the first advance of feed bar 95 occurs immediately after the ejection of an assembly A from assembly die 90. The second downward movement of bar 95 occurs after the full retraction of the assembly feed stem 38, to insure the movement of an assembly into position in front of stem 38 for transfer into the crimping die 94. The second movement of knock-off plate 96 is substantially an idle movement, the first movement having served to remove any crimped primer projecting from crimping die 94 and adhering to the assembly which has ejected it from the crimping die.

Tape supply

The means for supplying and intermittently feeding tape in the manner above mentioned may be constructed as follows:

A roll of tape T is supported on a horizontal table 110 (Fig. 1) from which the tape passes through a guide identified generally by numeral 111 and secured to the end plate 11. From the guide the tape T passes to the left, along the side of the machine, around a roller forming part of a tape feed assembly identified generally by numeral 112, thence transversely through the machine, substantially along the left face of the center plate 13 and through the various guide and supporting slots heretofore mentioned.

The tape feeding means, reference being made to Figs. 6, 7 and 9, may be constructed as follows:

To a bracket 113 secured to the fixed center plate 13 is attached a bearing block 114 preferably of an anti-friction metal. The bearing block 114 comprises longitudinal slots adapted to receive for reciprocating movement therein guide bars 116, 117 and 118 secured to or integral with a transversely slotted head 115. Mounted in the head 115 is a spindle 119 carrying the aforemen-

tioned tape guiding and turning roll 120 and projecting beneath head 115 to afford a spring engaging surface 121 and support a cam follower roll 122. Cam follower 122 is engaged during part of each revolution by the face of a barrel cam 123 secured to cam shaft 15, the configuration and location of the cam being seen by reference to Figs. 1 and 6 to be such that the cam follower and parts associated therewith are cammed outwardly once on each revolution of shaft 15 in properly timed relation to the movement of the parts heretofore described. The displacement of the feed device by cam 123 is resisted, and the device is restored to normal position, by a helical torsion spring 124, one end of which is formed into a hook 124a engaging the aforementioned surface 121 and which is appropriately clamped at its other end 124b upon the center plate 13. The outward movement of the follower roll 122 carries with it the hook 124a on the spring, thus further tensioning the spring. As the cam disengages from the roll 122 the tensioned spring asserts itself and returns the assembly to its normal or inward position.

To the side of fixed bearing block 114, opposite its attachment to bracket 113, is secured a plate 125 having secured thereto or struck outwardly therefrom an overturned lip 126 carrying an adjustable screw 127 designed to engage a post 128 secured between the plates 129 and 130 in the reciprocating tape feed assembly, to prevent inertia overthrow of the reciprocating assembly on its cam-urged outward movement. To the parts 116 and 117 of the reciprocating assembly are secured a lower plate 129 and an upper plate 130, which plates project laterally beyond the fixed plate 125 and are formed with bosses 131-132 which are apertured to receive a stud 133. Mounted on stud 133 and between the bosses 131-132 is a finger 134 urged to counter-clockwise (Fig. 7) rotation by a spring 135. An outwardly projecting finger piece 136 secured to or integral with the finger 134 enables manual lifting of the finger 134 when desired. Finger 134 projects through a slot 137 in the plate 125 and tends to engage the outer face of the bar 118 of the reciprocating assembly. The tape passes between the end of finger 134 and the adjacent surface of the bar 118, which surface may be somewhat roughened to improve its tape gripping characteristics. Thus, when the reciprocating assembly is moved to the right (Fig. 7) by spring 124, the tape is gripped between the roughened surface of bar 118 and the end of finger 134 and is advanced by an amount equal to the length of the reciprocating movement of the feed assembly. However, the inclination of finger 134 with respect to the surface of bar 118 is such that when the feed assembly is moved to the left under the action of cam 123, the finger merely slides upon the tape surface. Moreover, as above noted, the tape is at this time positively held from reverse movement by the engagement therein of the blanking punch 63 and the perforating punches 59. To enable accurate adjustment of the stroke of the tape feed assembly, an adjustable screw 138, threaded into an aperture in bearing block 114 abuts the adjacent face of head 115, access to the screw being had through a counterbored opening 76 in said head.

What is claimed is:

1. In a machine for the assembly of a plurality of components into a unitary structure, a fixed die plate having secured therein an assembly die, a pair of reciprocating gates disposed on opposite

sides of said fixed die plate; means within said die plate for sequentially positioning components of one class in front of said assembly die, means mounted on one of said gates for sequentially transferring components thus positioned into said die, a transfer stem guided in said second gate for reciprocation therethrough, means within the second of said gates for receiving a second class of components and sequentially positioning said components in front of said transfer stem, and means for actuating said transfer stem to transfer said second component into the first component held in said die.

2. In a machine for the assembly of electric primers comprising a body, an insulating disk and a contact button; a fixed die plate comprising an assembly die, a pair of reciprocating gates disposed on opposite sides of said fixed die plate, tools projecting from said gates toward and into apertures in said fixed die plate and guided therein, means for introducing body components into said fixed die plate, means for introducing contact buttons into one of said gates, means for sequentially transferring body components into said assembly die, means mounted on one of said gates arranged to sequentially position insulating disks between and in alignment with the body component in said assembly die and a contact button in said gate, means for sequentially transferring each contact button and the insulating disk in alignment therewith into the body component in said assembly die, and means for sequentially ejecting assemblies from said assembly die as an incident to the sequential placement of body components therein.

3. Apparatus for the assembly of an electric primer comprising a body and a contact button; said apparatus comprising a fixed die plate having therein an assembly die, means for sequentially transferring bodies into said die, a reciprocating gate having therein a hollow member defining a passage in alignment with said die, means for sequentially positioning contact buttons in said passage in alignment with said die, means for reciprocating said gate to position the end of said hollow member in proximity to the end of a body held in said die, and means movable independently of the movement of said gate for transferring contact buttons through said passage into a body held in said die.

4. In a machine for the assembly of electric primers comprising a body, an insulating disk and a contact button; a fixed die plate comprising a die and a primer body receiving passage, means for sequentially transferring primer bodies from said passage into said die; a reciprocating gate having therein a contact button receiving passage, and a contact button transfer passage in alignment with said die; means for producing a disk of insulating material at the end of said transfer passage, and means movable independently of said gate for advancing a contact button through said transfer passage to engage said insulating disk and move both said insulating disk and said contact button into a primer body held in said assembly die.

5. Apparatus for the assembly of electric primers comprising a body, an insulating disk and a contact button, comprising in combination; a fixed die plate having therein an assembly die, means for sequentially delivering primer bodies to said assembly die, means for feeding a tape of insulating material to a position in front of said die; a reciprocating gate comprising a contact button receiving passage, and a contact but-

ton transfer passage in axial alignment with said die, means secured to said gate for severing a disk of insulating material from said tape and holding said disk in alignment with said transfer passage, and means for moving a contact button through said transfer passage to engage said insulating disk and carry both said disk and said contact button into the primer body held in said assembly die.

10 6. Apparatus for the assembly of electric primers comprising a body, an insulating disk and a contact button, said apparatus comprising in combination; a fixed die, means for sequentially positioning the primer bodies in said fixed die, means for feeding a tape of insulating material to a position in front of said die, a reciprocating gate comprising a contact button transfer passage in alignment with said die, means secured to said gate adapted upon reciprocation thereof to sever a disk of insulating material from said tape, means for sequentially positioning contact buttons in said contact button transfer passage, yieldable means for retaining a contact button so positioned in an upright position in said passage, a contact button transfer stem associated with said gate and movable therewith as said gate is advanced to sever said disk from said tape, and means for advancing said contact button transfer stem through said contact button transfer passage to carry both a contact button and an insulating disk into the primer body held in said die.

7. In a machine for the assembly of a plurality of components into a unitary structure comprising in combination; a fixed die plate having secured therein a plurality of dies, a passage wholly within said plate for sequentially positioning components of one class in front of one of said dies, a second passage wholly within said plate for receiving assemblies ejected from said first die and sequentially positioning said assemblies in front of a second die, a pair of reciprocating gates disposed respectively on opposite sides of said fixed die plate, tools projecting from said gates toward said fixed die plate and guided in apertures therein for cooperation with said dies, means within one of said reciprocating gates for receiving a supply of components of a second class and sequentially aligning said components with said first die, and means reciprocably mounted on said one of said reciprocating gates and reciprocable through and independently of the reciprocation of said gate for sequentially transferring said components of the second class through said gate into a component of the first class held in said first die.

8. In a machine for the assembly of electric primers comprising a body, an insulating disk and a contact button, in combination; a fixed die plate, means for maintaining a supply of bodies in said fixed die plate and for transferring said bodies sequentially into an assembly die secured therein, means for holding a supply of insulating tape, indexable means for advancing said tape to a position in front of said assembly die, intermittently moving tape feeding means, tape perforating means, means for guiding the perforated tape to a position in front of said assembly die, a reciprocating gate, means within said gate for maintaining a supply of contact buttons, means movable with said gate for severing a disk of insulating material from said tape, contact button transfer means, and means for actuating said gate and said contact button transfer means to

assemble an insulating disk and a contact button into a primer body held in said die.

9. Apparatus for the assembly of a plurality of components including a body and a perforated disk of flexible material: said apparatus comprising in combination an assembly die; means for sequentially positioning bodies in said die; a supply of flexible tape; tape feeding means comprising a reciprocating tape gripping device; means for holding said tape against retrograde movement with said reciprocating gripping device, said holding means comprising a reciprocating tape perforating device and a hollow reciprocating disk cutting device; driving means, and connections from said drive means for actuating said gripping device, said perforating device and said disk cutting device respectively in such synchronism that said perforating device and said disk cutting device extend through said tape throughout the retrograde movement of said gripping device; and transfer means reciprocable through said disk cutting device to transfer a disk into a body held in said die.

10. Apparatus for the assembly of an electric primer comprising a body, an insulating disk and a contact button; said apparatus comprising a fixed die plate having secured therein an assembly die and a crimping die, a primer body passage within said plate terminating in a support adapted to sequentially position primer bodies in alignment with said assembly die, a primer assembly passage within said plate adapted to receive assemblies ejected from said assembly die and conduct said assemblies to a position in front of said crimping die, a removable support for the assembly in front of said crimping die, a feed bar in said assembly passage, means for reciprocating said feed bar, a reciprocating gate disposed on one side of said die plate, a body transfer stem and an assembly transfer stem projecting from said gate into apertures in said die plate in alignment with said assembly die and crimping die respectively, means for reciprocating said gate to cause said transfer stems to simultaneously advance a body and an assembly into said assembly die and crimping die respectively while ejecting from said dies respectively an assembly and a crimped primer, a second reciprocating gate disposed on the opposite side of said die plate, a disk cutter on said second gate projecting therefrom toward and into said die plate for positioning an insulating disk in alignment with said assembly die, means in said second gate for holding a contact button therein in alignment with said disk cutter and assembly die, means reciprocably mounted on said second gate and movable independently of said second gate for transferring said button and said disk into a body held in said assembly die, and a crimping head on said second gate projecting therefrom in alignment and for cooperation with said crimping die.

11. Apparatus for the assembly of an electric primer comprising a body, an insulating disk and a contact button; said apparatus comprising a fixed die plate having secured therein an assembly die and a crimping die, a primer body passage within said plate terminating in a support adapted to sequentially position primer bodies in alignment with said assembly die, a primer assembly passage within said plate adapted to receive assemblies ejected from said assembly die and con-

duct said assemblies to a position in front of said crimping die, a reciprocating gate disposed on one side of said die plate, a body transfer stem and an assembly transfer stem projecting from said gate into apertures in said die plate in alignment with said assembly die and crimping die respectively, means for reciprocating said gate to cause said transfer stems to simultaneously advance a body and an assembly into said assembly die and crimping die respectively while ejecting from said dies respectively an assembly and a crimped primer, a second reciprocating gate disposed on the opposite side of said die plate, a hollow disk cutter on said second gate projecting therefrom toward and into said die plate for placing an insulating disk in alignment with said assembly die, means in said second gate for holding a contact button therein in alignment with said disk cutter and assembly die, means reciprocably mounted on said second gate in alignment with said hollow disk cutter and movable independently of said second gate for transferring said button through said disk cutter and carrying said button and said disk into a body held in said assembly die, and a crimping head on said second gate projecting therefrom in alignment and for cooperation with said crimping die.

12. Apparatus for the assembly of an electric primer comprising a body, an insulating disk and a contact button; said apparatus comprising a fixed die plate having secured therein an assembly die and a crimping die, a primer body passage within said plate terminating in a support adapted to sequentially position primer bodies in alignment with said assembly die, a primer assembly passage within said plate adapted to receive assemblies ejected from said assembly die and conduct said assemblies to a position in front of said crimping die, a removable support for the assembly in front of said crimping die, a feed bar in said assembly passage, means for reciprocating said feed bar, a reciprocating gate disposed on one side of said die plate, a body transfer stem and an assembly transfer stem projecting from said gate into apertures in said die plate in alignment with said assembly die and crimping die respectively, means for reciprocating said gate to cause said transfer stems to simultaneously advance a body and an assembly into said assembly die and crimping die respectively while ejecting from said dies respectively an assembly and a crimped primer, a second reciprocating gate disposed on the opposite side of said die plate, a disk cutter on said second gate projecting therefrom toward and into said die plate in alignment with said assembly die, contact button holding and transfer means mounted on said second gate, and a crimping head on said second gate projecting therefrom in alignment and for cooperation with said crimping die.

GEORGE R. ECKSTEIN.
